UNITED STATES PATENT OFFICE.

OLIVER D. JOHANTGEN, OF CHICAGO, ILLINOIS.

REGISTER MECHANISM FOR COMPUTING-MACHINES.

1,301,943.

Specification of Letters Patent. Patented Apr. 29, 1919.

Original application filed May 29, 1916, Serial No. 100,531. Divided and this application filed October 29, 1917. Serial No. 198,959.

To all whom it may concern:

Be it known that I, OLIVER D. JOHANTGEN, a citizen of the United States, residing at Chicago, in the county of Cook and State 5 of Illinois, have invented a certain new and useful Improvement in Register Mechanism for Computing-Machines, of which the following is a full, clear, concise, and exact description.

10 My invention relates to improvements in computing machines and more particularly to the accumulator mechanism or register. The object of the invention is to provide an improved register which may be used to effect either addition or subtraction.

15 The preferred form of register illustrated in the drawings and described herein, is designed more particularly for use with a ten key adding and listing machine of the type disclosed in my two copending applications, Serial Numbers 100,530, and 100,531, both filed May 29th, 1916, the present application being a division of application No. 100,531. The invention is not limited to its 20 use with machines of this type however, as many of the features thereof are adapted for a wide range of application to computing machines generally.

25 Referring to the drawings:

30 Figure 1 is a sectional elevation of mechanism embodying the invention;

Fig. 2 is a top plan view thereof;

Figs. 3 and 4 show details of the subtraction key mechanism;

35 Figs. 5 and 6 show the accumulator and carrying mechanism in two different positions;

Fig. 7 is a top plan view of the mechanism in the lower part of the carriage;

40 Fig. 8 is a perspective view of a bell crank lever;

Fig. 9 is an elevation of a carrying plate; and

Fig. 10 is a top plan view thereof.

45 As an aid in understanding the details of the register and the mechanism associated therewith, of which the carriage is composed, the following brief description is given of the operation of the machine as a 50 whole.

To enter the items in the machine, the operator depresses digit keys which position a single, combined accumulator actuating

rack and type rack. The carriage is moved transversely across the machine with a step 55 by step movement as the keys are actuated, whereby said rack is engaged successively by the accumulator wheels.

The rack, which is elevated a variable amount by the depression of the digit keys, turns the accumulator 60 wheels and immediately thereafter is thrown rearwardly, striking against the platen to print the digits of the item, one at a time.

In the embodiment of the invention illustrated more fully in the prior application, 65 Serial Number 100,530, previously referred to, the keys are depressed in the order corresponding to the natural order in which the digits are read, namely, from left to right.

To permit this operation, the carriage is first 70 manually moved to the right by the operator by means of a lever having keys thereon which determine the extent of the throw of

said lever and hence stop the carriage in a position corresponding to the digit of the 75 highest order. The carriage thereafter moves from right to left, step by step, to the position corresponding to the digit of the lowest order.

If the machine is designed for operators accustomed to set the item 80 backward, that is, from right to left, the escapement mechanism and certain associated parts, may be reversed to permit operation of the carriage in the reverse direction.

The accumulator carriage comprises a 85 pair of side plates 10, 11, connected by various transverse members hereinafter referred to. A cover plate 12 is arranged at the front of the carriage which extends upwardly and partially over the top, being 90

provided with a sight opening 13 through which the numeral wheels are visible. A bottom plate 14 is secured to said side plates, which are connected also at their rear by a transverse plate 15, carrying a stud 16 with 95

a roller or pulley 17 mounted thereon. The carriage is supported at its rear end by means of said roller which rides along a cross rod 18 mounted at opposite ends in

brackets 19 secured to the body 20 of the 100 machine, said rod passing through openings 21 in the side plates 10, 11, and clearing the latter. The forward portion of the carriage is supported on a yoke 22 associated

105 with suitable escapement mechanism located in the body of the machine, whereby said

carriage is given a step by step movement across the machine. It is moved in the opposite direction by a manually operated setting lever 23, pivoted to the body of the machine at 24.

- The accumulator or register is actuated by a rack 25 (Fig. 1), which rack is reciprocated or differentially positioned in a vertical direction by key actuated mechanism 10 in the body of the machine. It may also be moved forward and backward slightly by a printing lever 26, which has sliding engagement therewith by means of a stud 27 and slot 28 (Fig. 5). Said lever 26 is 15 arranged to lock the carriage against movement, and has a projection 29 thereon adapted to perform other functions to be described. As the rack is being elevated, it is in engagement with some one of a series 20 of idler wheels 30 constituting part of the accumulator, and mounted on a shaft 31, the latter being carried in a pair of arms 32 mounted to turn about a pair of studs 33, 34, secured to the side plates 10, 11. 25 Said idler wheels, as shown in Fig. 1, are in mesh with a series of gear wheels or totalizer wheels 35 mounted on a shaft 36. Each totalizer wheel has a numeral wheel 37 arranged to turn therewith. Said numeral wheels are adjacent to the previously 30 mentioned sight opening. A series of register wheels 38 supported on a shaft 39 are also arranged in engagement with the totalizer wheels 35. If the arms 32 are swung 35 downwardly through a small angle, the idlers 30 will be moved out of mesh with the totalizer wheels 35 and moved into mesh with the register wheels 38. This latter is the subtraction position, in which rotation 40 of the idlers 30 by the rack will be communicated directly to the register wheels, the numeral wheels having their rotation reversed.

- The carrying is effected by collars 40 45 each having a single tooth 41 thereon, each collar being arranged to turn with one of the register wheels 38. Whenever one of said wheels completes its rotation, the tooth 41 engages a finger 42 constituting part of 50 a substantially T-shaped carrying plate 43. (Figs. 9 and 10.) There are a series of such plates, one in each of the spaces between the wheels 38 and each is pivoted on a stud 44 on an arm 45 mounted on a shaft 46 and 55 normally held in the position shown by a spring 46'. The end of the finger 42 is cut away, as shown in Figs. 9, 10, the cutout part being pressed between the teeth of the adjacent register wheel; the one above the 60 one shown in Fig. 1. The position of the plate 43 with respect to the arm 45 is maintained by a small rectifying lever 47 pivotally mounted on the arm 45 and held against the flat head of the T by a spring 48 as 65 shown. Said T-plate tends to remain in

the position shown but when swung about its pivot 44 through a small angle by the carrying tooth 41, it advances the next wheel 38 an amount corresponding to one tooth, further rotation being prevented by the engagement of the point 49 of the T with one of the teeth on said gear, (Fig. 6). The totalizer wheels 35, which are always in mesh with these register wheels 38, are thereby advanced by this carrying action. 70 The angular movement of said finger is limited by the rectifying lever 47 which strikes a stop 49' on the arm 45. This prevents complete rotation of the T-plate. It will be noted that the operation is the same regardless of the direction of rotation of the gear 38, except that the T-plate is moved in the opposite direction and the opposite corner 49 then acts as a holding pawl. The carrying device is therefore operative either 80 for addition or subtraction.

The carrying action is very rapid, since the finger 42 is pressed radially inward toward the center of the register wheels 38, the arrangement being similar to a toggle. 90 As long as said finger remains on the dead center, there is no carrying movement, but as soon as said finger is moved out of radial alignment by the carrying tooth 41, the spring 46' throws the plate 43 and the finger 95 42 rearwardly, thereby completing the carrying movement begun by the tripping of the finger 42 by the tooth 41.

The effect of the spring 48 on the rectifying lever 47 is to tend to restore the T-plate 100 to normal position and to permit the finger to act as a spring lock to resist rotation of the register wheels, when in normal position. Such return to normal position however, if permitted, would rotate the gears 30, 35, 38. 105 Said rotation therefore is opposed by the pawl 50 which is held in frictional engagement with the wheel 35 by the spring 51. Said T-plates may be restored to normal position however, by means of the rectifying 110 levers 47 and their springs 48, if the arms 45 on which they are mounted are moved forwardly. Such forward movement is accomplished by a cross rod 52 carried by a pair of pivoted arms 53 which are pivotally 115 mounted on the shaft 46 on opposite sides of the group of carrying devices. The lower ends of said arms 53 are connected by a second cross bar 54. The forward movement of said cross bars is effected by means 120 of a lever 55 which is pivoted about the stud 56 and carries a grooved roller 57 the latter engaging the cross bar 54 and swinging the same forwardly as the lever 55 rotates about its pivot (Fig. 7). Said lever 125 is moved by a stud 58 which projects downwardly through a curved slot 59 in the bottom plate 14 of the carriage. The lower end of said stud is received within a slot 60 in the carriage setting lever 23. Prior to the 130

time the stud 58 reaches the end of the slot 59, a shoulder 60' on said arm engages a pin 61 on a plate 62 which is mounted to reciprocate on the base plate 14 of the carriage. Said plate is guided by pins 63, 64 secured to said base plate and projecting through slots 65, 66 therein. It also has a notch 67 adapted to receive the lower end of a latch herein-after described. The general function of said plate 62 is to move the printing lever 26 out of the notches 68 in the rear of the base plate 14. This removal unlocks the carriage which is otherwise locked against lateral movement by said lever and said notches. Movement of said lever moves the rack 25 rearwardly, thereby withdrawing it from engagement with the idlers 30 whereby the carriage may be moved laterally without interference between said rack and said idlers. As the carriage setting lever is moved laterally by the operator, the arm 55 is first swung to the limit of movement permitted by the slot 59 after which the carriage as a whole travels laterally.

In a machine where it is desired to enter the item by depressing the digit keys in their natural order, namely from left to right, and the carriage is therefore to be moved from right to left, the following mechanism is provided:

Denominational or order keys 70 are mounted on the carriage setting lever 23 and serve when depressed to act as stops and limit the throw of said lever and hence of said carriage. Said keys are normally held in uppermost position by springs 71. When any one is depressed and the lever swung to the right, the lower end of said pin engages the forward end of a stop lever 72 thereby swinging said lever about its pivotal support 73 mounted on the body of the machine. An arm 74 on said stop lever is swung forwardly and engages a toothed plate 75 mounted on the under side of the carriage, thereby positively locking the carriage and the lever against further movement. The carriage is thus swung to the position corresponding to the highest order of the item to be registered, and thereafter the depression of the digit keys operates the escapement mechanism, whereby the successive idler wheels 30 are brought into mesh with the rack *seriatim* until the carriage reaches its initial position.

If the machine is to be constructed to permit the item to be entered from right to left, the denominational keys 70 may be omitted and the escapement mechanism and setting lever reversed, whereby the carriage may move from left to right as the operator depresses the digit keys, and may subsequently be restored to normal position by said lever or some other manually operated device.

To effect subtraction, the subtraction key

80 is pressed rearwardly. Said key is mounted on a stud 81 in the frame of the machine and also on a stud 82 mounted in a member 83, the latter being pivoted about the stud 84. Said studs 81, 82 pass through suitable slots 85, 86 in said key. A link 87 is also mounted on said studs and has a slot 88 at one end, a little shorter than the companion slot 85, and having a hole 89 in the opposite end. It also has a downwardly projecting lock 90. A latch 91 having the form of a bell crank lever is mounted adjacent said key on a stud 92, the lower end of said latch fitting within the notch 67 in the reciprocating plate 62 (Fig. 7). Said latch 80 has a lateral projection 93 thereon which is arranged in the path of a projection 94 on the subtraction key. The rear end of said projection 94 is beveled, whereby as said subtraction key is pressed rearwardly, said bevel rides over the lateral projection 93 thereby rocking the latch and moving the plate 62 and the printing lever 26 to the rear, thus moving the rack 25 out of engagement with the idlers 30, which engagement would interfere with the swinging of said idlers to subtraction position.

Prior to the actuation of the subtraction key 80, the link 87 is in its forward position with its projection 90 in front of the lateral extension 93. This locks the member 83 against movement, thereby preventing accidental movement of the accumulator from addition to subtraction position, such as might be caused for example, if the rack 100 were in engagement with the idlers. Before the subtraction key reaches the end of its rearward movement, the stud 82 is engaged by the end of the slot 86, rocking the member 83 and drawing the link 87 to the rear 105 until its projection 90 is to the rear of the lug 93, at which time the accumulator gears have been moved to subtraction position. Simultaneously, the projection 94 snaps over the lug 93 thereby permitting the plate 62 to 110 restore the latch 91 to normal position, the subtraction key being thereby locked against return movement by the projection 93.

The spring 96 tends to hold the parts in addition position unless they are positively locked in subtraction position. After the item has been subtracted, the operator before setting up another item for addition, swings the carriage setting lever to one side as previously described, thereby moving the plate 120 62 to the rear, this movement serving to swing the latch 61 sufficiently to release the subtraction key 80 and to permit it and the link 87 to be restored to normal position. The restoration to addition position is therefore accomplished automatically. This automatic action prevents oversight on the part of the operator who might leave the machine set for subtraction, whereas he may intend to add the subsequent items.

The platen and ribbon feed mechanism may be of any suitable construction and need not be described herein.

It is to be understood that the invention is not limited to the embodiment thereof shown and described in detail herein, as it may be embodied in various other forms, within the scope of the appended claims.

What is claimed is:

- 10 1. An adding machine carriage, comprising a plurality of idler wheels, a plurality of numeral wheels, and a plurality of register wheels, said idler wheels being arranged to reverse the movement of said numeral wheels, a transfer mechanism consisting of a series of fingers normally engaged between the teeth of said register wheels, means turning with said register wheels for throwing said fingers to directly advance the wheels engaged thereby, means associated with said fingers for limiting said movement to a single tooth, and means for restoring said fingers to normal position.
- 15 2. An adding machine carriage, comprising a plurality of idler wheels, a plurality of numeral wheels, and a plurality of register wheels, said idler wheels being arranged to reverse the movement of said numeral wheels, a transfer mechanism consisting of a series of fingers normally engaged between the teeth of said register wheels, means turning with said register wheels for throwing said fingers to directly advance the wheels engaged thereby, means associated with said fingers for limiting said movement to a single tooth, means for withdrawing said fingers from said teeth and means for restoring them to normal position.
- 20 3. In a transfer mechanism, a series of register wheels, a series of T-shaped latches engaging the same, supports for said latches, a series of spring members held against the heads of said T latches to maintain them in normal position, the points at the ends of said heads acting as stops to prevent overthrow of said wheels when engaging the teeth thereof, means associated with said wheels for tripping said latches, and means for moving said supports to restore said latches.
- 25 4. In combination, a single actuating rack, a plurality of trains of accumulator gears actuated one at a time by said rack, numeral wheels rotated by said gears, means for changing the relative arrangement of the gears of each train to permit reverse rotation of said numeral wheels, thus effecting subtraction, a carrying mechanism having fingers normally engaging the teeth of one of the gears in each train, and means for throwing said fingers in either direction to directly advance the wheels of the next

higher order to indicate the carrying operation either during addition or subtraction and spring-actuated means for completing said carrying operation.

5. In combination, a single actuating rack, trains of accumulator gears actuated thereby *seriatim*, numeral wheels turned by said gears, means for changing the relative arrangement of said gears to reverse the rotation of said numeral wheels, carrying mechanism consisting of a series of pivoted arms, springs therefor impelling said arms toward one of the gears of each train, a finger on each arm pressed radially between the teeth of said gear, spring means tending to maintain said finger in radial position, a carrying tooth associated with said gear and arranged to move the finger of the adjacent gear out of radial position to effect a transfer either backward or forward, and means associated with said rack for swinging said arms away from said gears to permit restoration of said fingers to radial position.

6. In combination, an accumulator consisting of a plurality of trains of gear wheels, a rack for said accumulator, said rack and accumulator being relatively movable to permit coöperation of said rack with one of the gears of each train *seriatim*, a series of carrying fingers; a movable support therefor, means for holding said fingers radially with respect to one of the gears of said trains, means impelling said supports toward said accumulator to press said fingers between the teeth of said gears, means associated with said gears for moving said fingers out of radial position to effect carrying, means associated with said supports for limiting the movement of said fingers with respect thereto, and means coöperating with said rack and with said supports to permit withdrawal of said fingers from said gears and restoration thereof to radial position.

7. In a carriage mechanism, a series of register wheels, a corresponding series of carrying fingers, a series of movable supports therefor, said fingers being pivoted to said supports, springs pressing said fingers radially against the teeth of said register wheels, and carrying teeth associated with said register wheels for throwing said fingers off the dead center upon rotation in either direction, whereby said springs cause said fingers to advance the respective wheels of the next higher order one unit in either direction to effect transfer either in addition or subtraction.

In witness whereof, I hereunto subscribe my name this 26th day of October A.D., 1917.

OLIVER D. JOHANTGEN.
